(57) CLAIM

The ornamental design for a portable and removable enclosure for a recreational vehicle, as shown and described.

DESCRIPTION

FIG. 1 is a front perspective view of the portable and removable enclosure for a vehicle of the present invention; FIG. 2 is a back perspective view of the invention of FIG. 1;

FIG. 3 is a front view of the invention of FIG. 1;

FIG. 4 is a back view of the invention of FIG. 1;

FIG. 5 is a side view of the invention of FIG. 1, as seen from a left side of FIG. 3;

FIG. 6 is a side view of the invention of FIG. 1, as seen from a right side of FIG. 3;

FIG. 7 is a top view of the invention of FIG. 1; and,

FIG. 8 is a bottom view of the invention of FIG. 1.

The broken line showing a vehicle is included for contextual purposes and forms no part of the claimed design.
